ROTATABLE BLADE CLAMPING SAFETY RAZOR

Paul Hoberg, Brooklyn, N. Y.

Application October 30, 1952, Serial No. 317,681

4 Claims. (Cl. 30—60.5)

This invention relates to new and useful improvements in safety razors of the type adapted to receive a thin flexible double-edge blade.

More particularly, the present invention proposes the construction of an improved hoe-type razor having a pair of rotatable blade clamping members which can be operated by twisting a part of the handle and which by novel structure will securely clamp a razor blade and lock it in position for shaving use.

Another object of the present invention proposes forming the safety razor with a tubular handle rod having its side walls cut to form a camming and locking groove for use with a removable handle pin to operate and lock the blade clamping members.

Still further, the present invention proposes constructing the razor with a solid handle rod having a camming and locking groove formed in it for operating and locking the blade clamping members.

As a further object, the present invention proposes providing a spring biased plunger at the blade clamping member engaging the end of the handle rod to assist in operating the blade clamping members.

The present invention further proposes the novel arrangement of a single head plate for simplicity of construction and a closed bottom head plate with blade clamping member pivoting bars for obtaining the advantages of a closed type structure without interfering with the operation of the blade clamping members.

Another object of the present invention is to provide blade clamping members each having a handle rod receiving groove with an end-locking lug at one end adjacent thereto and a positioning groove at other end opposite the locking lug.

A further object of the present invention is to provide a novel blade clamping member having end extensions to fully cover the width of a razor blade when in clamping position.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view illustrating the razor of the present invention with a blade held therein and parts broken away.

Fig. 2 is a view similar to Fig. 1 but showing the blade clamping members in raised position and the blade removed.

Fig. 3 is a side elevational view of the razor in the position illustrated in Fig. 2.

Fig. 4 is an exploded view of the razor shown in Figs. 1 to 3, inclusive.

Fig. 5 is a bottom plan view of the head plate illustrated in the several figures and of the blade clamping members in the position shown in Figs. 2 and 3.

2

Fig. 6 is a view similar to Fig. 5 but showing the blade clamping members in the position shown in Fig. 1.

Fig. 7 is a top plan view of the structure shown in Fig. 1 but with the blade removed.

Fig. 8 is a sectional view of a handle rod structure illustrating a modification of the present invention.

Fig. 9 is an elevational view, partly in section, of another handle rod structure illustrating another modification of the present invention.

Fig. 10 is a bottom plan view similar to Fig. 5 but illustrating a further modification of the present invention.

Fig. 11 is a top plan view of the structure shown in Fig. 10.

Fig. 12 is an end view of the head plate structure shown in Fig. 11.

Fig. 13 is a perspective view of another blade clamping member illustrating a still further modification of the present invention.

Fig. 14 is a top plan view of still another blade clamping member illustrating another modification of the present invention.

Fig. 15 is an end view of the structure shown in Fig. 14.

The safety razor, in accordance with the first form of the invention illustrated in Figs. 1 to 7, inclusive, has a hollow handle 20. A handle rod 21 extends through handle 20 having a central portion 22 rotatable in the handle and an end portion 23 adapted to extend from the bottom of the handle. End portion 23 preferably is of the same outside diameter as the handle 20, both preferably being round in cross-section, and the central portion 22 is of smaller diameter. End portion 23 may be knurled as shown for ease in rotating the handle rod 21 in the handle 20.

A shank portion 24 of further reduced diameter is formed on the other end of the handle rod 21 with an end member 25 in the form of a rounded head. An abutment 26 is spaced from the end member 25 on the shank portion 24, the shank portion 27 of the handle rod 21 between the rounded head 25 and the handle rod abutment 26 being of still further reduced cross-section to form the handle rod abutment 26.

Central portion 22 of the handle rod 21 is tubular and a locking slot 28 with an inclined camming slot 29 is formed in its walls, the inclined camming slot extending from the locking slot toward the end member 25.

Handle 20 has a pin opening 30 (Fig. 4) extending through one side wall, and a pin 31 removably extends through the pin opening 30 for engagement with the handle rod slots 28 and 29. Handle 20 also has a sleeve bracket 32 secured to its upper end.

A head plate 33 is removably secured to handle 20, the plate 33 being provided with screw holes 34 to receive screws 35 (Fig. 4) extending through sleeve bracket 32 on the handle 20.

Head plate 33 has a central opening 36 for the handle rod end member 25 and shank 24. Lateral slot openings 37 and 38 extend from the central opening 36 and a pair of blade clamping members 39 and 40 pivotally extend into the lateral slot openings 37 and 38 of the head plate.

Blade clamping members 39 and 40 have adjacent arcuately curved portions 41 and 42 each with a central opening 43 to pass the shank portion 27 of the handle rod 21, and abutment tongues 44 and 45 are provided on the blade clamping members. The abutment tongues 44 and 45 are adapted and positioned to underlie the end member or rounded head 25 of the handle rod 21 for rotating the blade clamping members 39 and 40 to open or blade-receiving position and to overlie the handle rod abutment 26 for closing the blade clamping members.

When the blade clamping members 39 and 40 are closed to retain the blade in position, as shown in Fig. 1, counterclockwise rotation of the knurled end portion 23 of the handle rod 21 is permitted by the inclined camming slot 29 in the central portion 22 of the handle rod 21 and pin 31. The permitted rotation is limited by the length of the slot 29 and pin 31 and moves the handle rod 21 downwardly in a retracted position relative to the handle 29 with the knurled end portion 23 of the handle rod 21 spaced away from the handle. This movement moves the undersurface of the rounded head end member 25 of the handle rod against the abutment tongues 44 and 45 of the blade clamping members 39 and 40 rotating these members until they are in the parallel abutting position shown in Figs. 2 and 3. In this position a blade 46 of the thin flexible double-edge type commonly available may be either inserted or removed from the razor.

A clockwise twist of the knurled end portion 23 of the handle rod 21 will turn and lock the blade clamping members 39 and 40 into blade retaining position by reason of the handle rod abutment 26 bearing against the blade clamping members abutment tongues 44 and 45.

The modified form of the invention shown in Fig. 8 is characterized by the provision of a handle rod 47 having a shank portion 48 slidably mounted in the end of a tubular central portion 49. Resilient means in the form of a coil spring 50 encircles the shank portion 48 and bears against an abutment 51 of the tubular portion 49 and an end piece 52 on the shank portion 48 to bias the shank portion and end member 53 of the shank portion 48 toward the central portion 49 of the handle rod. Stop means in the form of a shoulder 54 is provided adjacent to and spaced from the end member 53.

The modified form of the invention shown in Fig. 9 is characterized by the provision of a handle rod 55 of solid form with a locking slot 56 and inclined camming slot 57 formed in the solid central portion of the handle rod. A sleeve 58 held to the solid central portion by set screw 59 provides an end portion for turning the handle rod.

In the modified form of the invention shown in Figs. 10 to 12, inclusive, a head plate 60 is provided. Head plate 60 has a central opening 61 and spaced laterally extending recessed portions 62 and 63 with slat bars 64 and 65 mounted above the recessed portions 62 and 63, respectively. The blade clamping members 39 and 40, shown in Figs. 1 to 7, inclusive, pivotally extend around the slat bars into the recessed portions 62 and 63 of the head plate.

The modification of the invention illustrated in Fig. 13 is characterized by the provision of a blade clamping member 66 having end extension wings 67 and 68 at its outer sides, a pair of such members being used.

5 In the modified form of the invention illustrated by Figs. 14 and 15, a blade clamping member 69 is provided with a locking lug and rotation stop 70 at one end 71 and a positioning and locking groove 72 at the other end 73. A pair of such members are used, the 10 two being similarly constructed except that the groove 72 of one clamping member is disposed opposite the lug 70 of the other clamping member.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A safety razor comprising a hollow handle, a hollow handle-rod extending rotatably through said hollow handle, a head plate removably secured to said handle, and 25 a pair of blade-clamping members engaging said hollow handle-rod, said hollow rod having a shank portion extending through one end thereof, and tension means on said shank portion biasing said shank portion towards the central portion of the handle-rod.
2. The combination of claim 1 wherein said hollow rod includes an internal shoulder portion engaged by said tension means, said shank having an end member to receive the head plate.
3. The combination of claim 2 wherein the hollow handle includes an opening, a pin in said opening, and said handle rod having a spiral groove, said pin riding in said groove to open and close the razor.
4. The razor of claim 3 wherein said head plate retains said pair of blade clamping members, each member having a rotation stop lug at one end and a locking groove at the other end.
